(57) **CLAIM**

The ornamental design for a cover of a packing vessel, as shown and described.

DESCRIPTION

FIG. 1 is a perspective view of a cover of a packing vessel showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8—8 in FIG. 6; and,

FIG. 9 is a cross-sectional view taken along line 8—8 in FIG. 6 with the handles shown in an alternate position and showing the cover of my new design in use.

The broken line disclosure in FIG. 9 is for environmental purposes and does not form any part of the claimed design.
